SIMON WILLIAM CONWELL, OF MINERAL WELLS, TEXAS, ASSIGNOR OF ONE-TENTH TO
JOSEPHINE PORTEE, OF MINERAL WELLS, TEXAS, AND ONE-TENTH TO DAVID C.
KUDER, OF HOPEVILLE, IOWA.

COMBINED SEAT AND DESK.

Application filed February 21, 1924. Serial No. 694,305.

To all whom it may concern:

Be it known that I, SIMON W. CONWELL, a citizen of the United States, and resident of Mineral Wells, in the county of Palo Pinto and State of Texas, have invented certain new and useful Improvements in Combined Seats and Desks, of which the following is a specification.

My invention relates to improvements in combined seats desks and consists in the combinations, constructions and arrangements herein described and claimed.

An object of the invention is to provide a combined seat and desk in which both the seat and the desk can be adjusted vertically and secured in adjusted position.

A further object of the invention is to provide a device of the character described which is adapted to be secured to a supporting surface in such manner that it is not likely to be torn loose from the supporting surface during its use.

A still further object is to provide a device of the character described which comprises relatively few parts, can be packed into relatively small space for the purpose of shipment or storage, and which is thoroughly practical commercially.

Other objects and advantages will be apparent from the following description, considered in conjunction with the accompanying drawings, in which—

Figure 1 is a perspective view showing the combined seat and desk embodying the invention,

Figure 2 is a fragmentary rear elevation of the device.

The supporting or frame structure of the device includes a pair of bars, each of which is bent substantially into U-shape to provide a substantially straight intermediate portion 1, upstanding substantially parallel end portions 2 and 3 respectively and an outwardly bowed or substantially semi-circular portion 4 merging the end portion 3 and intermediate portion 1 one into the other. The end portions 2 are connected adjacent to their upper ends by a cross bar 5 and are connected adjacent to their lower ends or juncture with the intermediate portions 1 by a second cross bar 6.

The cross bars 5 and 6 are stayed to each other by intermediately crossed diagonally

extending bars 7 and 8 respectively, the latter being secured at their ends to the respective cross bars in position to brace the end portions 2 and also having the portions thereof that cross each other connected together, as at 9.

The end portions 3 are connected together and braced in substantially the same manner as the end portions 2 by upper and lower cross bars 10 and 11 respectively, and intermediately crossed diagonally extending bars 12 and 13 respectively.

With the arrangement described, corresponding portions of the bars 2—1—4—3 will be held in spaced parallel relation. The bars preferably are formed of a material possessing considerable inherent resiliency, such as steel.

The connected together and braced end portions 2 provide a support for a desk indicated at 14. The desk 14 has the form of a box-like case including a substantially vertical front wall 15 and a top that includes a hinged lid section 16. The top also includes an upstanding flange 17 at its front edge, the flange being in substantially vertical alignment with the front wall 15. Two vertically disposed attaching strips 18 are secured to the desk 14 at the front thereof, the respective strips being located adjacent to the opposite side edges of the desk front and preferably being disposed in recesses or cut outs in the front wall 15 so that the attaching strip will lie in the plane of the front wall 15. Each attaching strip is formed with a forwardly extending substantially T-shaped guiding and retaining member 19 at its upper end and with a forwardly and downwardly turned hook portion 20 at its lower end.

Each of the end portions 2 is provided with a vertical guide slot 21 that extends from a point adjacent to the upper end of the end portion 2 for part of the length of the latter and in line with a vertical series of spaced apart openings 22 that extends in the remaining portion of each of the end portions 2. Each of the vertical guide slots 21 has a width slightly greater than that of the stem of each T-shaped guiding and retaining member 19 and less than the width of the head portion of the guiding and retaining member and each

guide slot is enlarged laterally adjacent to its upper end as indicated at 23 so that the head portion of one of the T-shaped guiding and retaining members may be projected therethrough to position the stem of the guiding and retaining member in sliding contact with the walls of the guide slot. Each of the openings 22 is adapted to receive the hook portion 20 at the lower end of one of the attaching strips 18.

It will be manifest from the foregoing that the desk 14 will be attached to the end portions 2 of the supporting structure when the desk has been positioned above the intermediate portions 1 and the respective T-shaped guiding and retaining members 19 have been inserted in the enlarged upper end portions of the guide slots 21 to position to slide in engagement with the latter. The desk thus may be moved vertically along the supporting members 2 and may be firmly, although releasably, secured to the supporting member 2 in any one of a plurality of vertically adjusted positions by placing the hook members 20 in engagement with predetermined corresponding openings 22.

In order to adjust the position of the desk vertically from a given position, it only is necessary to move the desk slightly vertically until the hooks 20 can be moved out of engagement with openings 22 with which they are engaged and the desk then is moved to adjusted position and the hooks again placed in engagement with other of the openings 20.

The front wall of the desk lies flatwise against the bars of the desk support when the desk has been secured to the members 2 of the desk support in the manner described so that the desk will be firmly braced and normally held against movement relatively to the desk support.

The device also includes a seat 24 having a back 25 preferably formed integrally therewith. Two vertical attaching strips 26 are secured to the back 25 against the rear face thereof and adjacent to the side edges thereof. The attaching strips 26 are similar to the attaching strips 18 and each is provided at its upper end with a rearwardly extending T-shaped guiding and retaining member 27 and at its lower end with a rearwardly and downwardly extending hook 28. Each of the members 3 is formed with a vertical guide slot 29 enlarged laterally at its upper end, as at 30, and extending from a point adjacent to the upper end of the member 3 for part of the length of the latter.

Each guide slot 29 is in vertical alignment with a vertical series of spaced apart openings 31 in the lower portion of each member 3.

65 T-shaped guiding and retaining members

27 are adapted to be inserted in the enlarged upper end portions 30 of the guide slots in position to slide in engagement with the guide slots and the hooks 28 are adapted to engage with the openings 31, whereby the seats 24 may be supported on the members 3 in vertically adjusted position. A head or supplementary back rest 32 may be carried by the seat support at the upper end of the latter and substantially in alignment with the back 25.

From the foregoing description of the various parts of the device, the operation thereof may be readily understood. The device is particularly well adapted for use in school rooms and both the desk and seat or either the desk or the seat may be adjusted vertically to satisfy varying requirements, as for instance to adapt the device for use at different times by pupils of different sizes. The intermediate portions 1 of the bars of the supporting structure are spaced from a floor 33 or like supporting surface by depending projections, as indicated at 34, whereby the device satisfies sanitary requirements since dirt, sweepings and the like will not lodge and accumulate underneath the supporting structure, the desks being readily movable on the supporting projections 34 to permit cleaning therebeneath. These portions 1 comprise what may be considered a base. Since the members 3 to which the seat backs are attached are merged into the base members 1 by outwardly bowed members made of a material possessing inherent resiliency, the seat will be resiliently supported on the base, thus materially adding to the comfort of the user and the members 4 may be termed spring members connecting the seat support with the base. However, the spring members 4 are sufficiently stiff to prevent the seat from tilting back when the user leans against the back of the seat.

Obviously, my invention is susceptible of embodiment in forms other than that illustrated in the accompanying drawings and I therefore consider as my own all such modifications and adaptations of the form of the device herein described as fairly fall within the scope of the appended claims.

I claim:

1. In a device of the character described, a supporting structure comprising a pair of substantially U-shaped members, each formed of a single length of material having inherent resiliency and each consisting of a substantially horizontal intermediate portion, substantially parallel upstanding end portions and an outwardly bowed curved spring portion merging one of said end portions into said intermediate portion and cross members staying said U-shaped members to each other and holding said members in spaced parallel relation, said

upstanding end portions being adapted for connection with articles which are to be supported thereby.

2. In a device of the character described, 5 a supporting structure comprising a pair of substantially U-shaped members, each formed of a single length of material having inherent resiliency and each consisting of a substantially horizontal intermediate portion, upstanding end portions and an outwardly bowed curved spring portion merging one of said end portions into said
- intermediate portion, cross members staying said U-shaped members to each other and holding said members in spaced parallel relation, said upstanding end portions being adapted for connection with articles which are to be supported thereby, and spaced depending projections on the lower sides of said intermediate portions of the 15 U-shaped members for supporting the latter on a floor in spaced relation to the latter. 20

SIMON WILLIAM CONWELL.
